Hornbeck and Hornbeck

UNITED STATES PATENT OFFICE.

TRUMAN W. POST, OF NEW YORK, N. Y., ASSIGNOR TO ARMS PRODUCTS COMPANY, OF NEW YORK, N. Y., A CORPORATION OF NEW YORK.

ATTACHMENT FOR FIREARMS.

1,387,308.

Specification of Letters Patent.

Patented Aug. 9, 1921.

Application filed July 20, 1918. Serial No. 245,831.

To all whom it may concern:

Be it known that I, TRUMAN W. Post, a citizen of the United States of America, residing in the city, county, and State of New York, have invented certain new and useful Improvements in Attachments for Firearms, of which the following is a specification.

My invention relates to firearms and particularly to an attachment for taking up the recoil or kick incident to the discharge of the firearm. It consists broadly of a strut or like device, temporarily or permanently secured to the firearm at one end and adapted to rest against the ground or other base at its opposite end. It is intended for use primarily with such manually supported and discharged firearms as the ordinary service rifle, small, low-velocity howitzers, and the like, when firing small grenades, bombs, etc., the recoil from which is too great to be taken by the body without danger of injury. By providing means for taking up this recoil not only physical shock is eliminated, injury prevented, and nervous energy conserved, but also all mental faculties relieved from strain from this source, aim improved, and the faculties in general exercised to better advantage in the management of the firearm.

In the accompanying drawings,

Figure 1 is a perspective of a portable howitzer shown in position for use;

Figs. 2 and 3 are side elevations drawn to a larger scale, showing a howitzer of this type with my attachment secured thereto in different manners;

Figs. 4 and 5 are broken end and side elevations, respectively, of another modified construction of the attachment;

Fig. 6 is a broken side elevation of a still further modification;

Fig. 7 is a side elevation of an ordinary service rifle, showing my invention applied thereto in one form;

Fig. 8 is a side elevation of a howitzer showing the manner in which it is carried;

Fig. 9 is a side elevation showing the howitzer in position for firing;

Fig. 10 is a perspective of a harness by which the howitzer may be carried;

Fig. 11 is a longitudinal section through a sprag of modified construction;

Fig. 12 shows a howitzer supported by a sprag of this type in firing position; and

Fig. 13 is a side elevation of the end of a sprag, showing, in section, a modified construction of the abutment flange.

It has become common practice in the trenches to fire from the rifle, grenades or small bombs, and lately specially designed portable howitzers of small size have been brought into use for the same purpose. The recoil or kick occasioned by the discharge of grenades, is too great to be taken with safety by the operator, and, in any event, whether fired from the body or rested against a log or boulder, the likelihood of danger or the inconvenience of the position occupied by the grenadier has proven sufficient to interfere seriously with the most effective operation of the firearm. The present device is designed to afford a support for firearms of this type which will not only take up the recoil or kick, but will afford a relatively uniform, but adjustable, firing position for the piece, thus aiding in securing accuracy of aim.

In Fig. 1 I have indicated a light howitzer 10 which is supported from the body by harness (not shown) and held substantially

in the position indicated, when firing. To the breech end of the howitzer I have attached, in fixed position, a sprag 11, the lower end

12 of which is pointed to enter the ground, while the flange 13 adjacent the point af-

fords a thrust abutment which is particu-

larly serviceable when the ground is soft. Obviously, the flange 13 may be made of any desired size and shape. I have shown it as a relatively small disk, but this is only

for the purpose of illustration. The body of the sprag 11 is preferably of metal, al-

though it may be of any suitable material

which will stand the thrust strains incident

to the discharge of the firearm.

In Fig. 2 I have shown a sprag of this type pivoted on a pin 14 passing through

lugs 15 at the breech end of the howitzer 10

and held in position by a cotter pin 16. By

removing the cotter pin, the bolt 14 may be

withdrawn and the sprag 11 detached when

the howitzer is not in use. In the form

shown, the bolt 14 is round and affords a pivot joint, but obviously a square or polygonal bolt could be used which would lock the sprag in fixed position.

5 In Fig. 3 I have shown a sprag 11 with a somewhat longer shank which passes through a pair of guide eyes 17 and 18 mounted on the barrel of the howitzer. A set screw 19, carried by the guide eye 18, 10 is used to secure the sprag in longitudinally adjusted position.

In Figs. 4 and 5 I have shown a tubular sprag 20, to the end of which is secured a head 21 carrying a latch 22. The nose of 15 the latter engages a latch plate 23 secured to the breech of the howitzer 10 and having a hinged connection 24 to the head 21 of the sprag. When the howitzer is not in use, the sprag may be swung into out-of-the-way position on the hinge 24. When the howitzer is to be used and the sprag brought into play, it is merely swung down into alignment 20 with the howitzer, whereupon the latch 22 automatically engages the latch plate 23 under the action of the latch spring 25.

The tubular construction indicated in Figs. 4 and 5 may be utilized, as shown in Fig. 6, to afford a sprag of adjustable length. As there shown, the upper section 26 of the 30 sprag is tubular and secured to the breech of the howitzer 10. The lower end of the sprag is a rod 27, sliding in the tubular portion 26 and held in adjusted position by the thumb-screw 28.

35 In Fig. 7 I have shown my invention applied to the ordinary service rifle 29. For this purpose, the sprag 30 has at its gun end a socket 31 adapted to receive the stock 32 of the gun, to which it is detachably secured by a set screw 33 passing through the arm 40 of the socket.

In Fig. 8 I have shown the howitzer 10 hung upon a supporting body harness for transport. As seen in this figure, the howitzer is provided with muzzle and breech rings 35 and 36, respectively. On each ring is an eye 37, 38, adapted to receive a hook attached to the harness. The body harness, as here shown, comprises a breast belt 39 45 having a shoulder strap 40 adapted to pass over the right shoulder. Adjacent the rear terminus of this strap 40 is secured a carrying hook 41 which takes into the eye 38 of the breech ring 36 when the howitzer is 50 being carried. From the front portion of the breast belt 39 depends a tongue 42 having a hook 43 at its lower end. This hook engages the eye 37 of the muzzle ring 35 on the howitzer when the latter is supported 55 in firing position (Fig. 9). A harness of this type is not only very light but very simple, while, at the same time, affording considerable flexibility of adjustment, since both the shoulder strap 40 and the depend-

ing tongue 42 may be provided with take-up 65 buckles in a manner well understood in the art. Moreover, by hanging the howitzer at the right side of the body, not only is the sprag 11 held in a position in which it cannot get between the legs of the soldier to trip him, but it is possible to grasp it in the right hand and thus afford means by which the howitzer can be manually supported and steadied while marching.

In Fig. 11 I have shown another modified 75 construction of the sprag, which here comprises two half round bars 44 and 45 of equal length, adapted to be held together at one end by a cross pin 46 and at the other end by the bearing ring 47 which screws 80 upon a threaded, divided ferrule 48, as shown in Fig. 11. The end adapted to be attached to the howitzer is externally threaded at 49 to take into a tapped hole 50 in the end of the howitzer. When the howitzer is to be fired from the position shown in Fig. 9, the sprag will be attached in the manner shown in Fig. 11. On the other hand, if the howitzer is to be fired from the ground, it will be supported upon the sprag 85 as shown in Fig. 12. In this position, the two bars 44 and 45 are separated by unscrewing the ring 47 and the upper ends held in swivel joints 51 by pins 52 passing through the holes left open by the removal 95 of the cross pin 46. This gives a tripod support for the howitzer, the elevation of which may be altered by either spreading the legs 44-45 or by swinging the body of the howitzer on the pivots 53.

100 In Fig. 13 I have shown the sprag 11 provided with a thrust plate 54, which is spaced from its abutment flange 55 by a cushion 56 of resilient material, such as rubber. A modification of this type may be applied to 105 any of the sprag constructions illustrated. It is equally obvious that there may be various combinations of the several modifications shown, and the invention contemplates such combinations. Thus, it is perfectly 110 clear that the divided construction of Fig. 11 could be equally well applied to the construction of Fig. 3 or Fig. 6; while the modification of Fig. 13 could be applied to any 115 of the sprag abutment plates, and similarly it is understood that the howitzers of Figs. 2 and 6 may be provided with the carrying rings 35 and 36 and supported from a harness, as shown in Figs. 8 and 9. The particular location of the carrying rings is not 120 material, and the supporting eyes may be placed upon any suitable attachment or part of the howitzer.

125 Various other modifications of construction will readily occur to those dealing with the problem which do not, however, depart from what I claim as my invention, the essential feature of which is the provision of

means for protecting the grenadier from injury due to recoil on the discharge of a bomb-throwing firearm, and to relieve him, so far as possible, from the nervous strain now 5 commonly incident thereto.

I claim:

1. In ordnance, a portable firearm, a body harness for carrying the same, and a ground sprag forming, with the body harness, a support for the firearm in firing position. 10
2. In ordnance, a portable firearm, a body harness for carrying the same, and a ground sprag forming, with the body harness, a support for the firearm in firing position,

said sprag being attached to said firearm 15 in such position as to take up substantially all the thrust of recoil on firing.

3. In ordnance, a portable firearm, a body harness having readily disengaged means for supporting said firearm in one position 20 for transport and in another position for firing, in combination with a sprag associated with said firearm and forming a grounded thrust bearing therefor when supported in firing position on said harness. 25

In testimony whereof I have signed my name to this specification.

TRUMAN W. POST.
